UNITED STATES PATENT OFFICE.

WALTER A. O'BANNON, OF TULSA, OKLAHOMA.

PUMP PACKING.

Application filed September 22, 1924. Serial No. 739,052.

To all whom it may concern:

Be it known that I, WALTER A. O'BANNON, a citizen of the United States, and resident of Tulsa, in the county of Tulsa and State 5 of Oklahoma, have invented certain new and useful Improvements in a Pump Packing, of which the following is a specification.

The invention relates to packings which are used to prevent leakage between two 10 relatively movable, telescoping members and has an important utilization in connection with packing for pumps for use in oil or other deep wells. In this type of pump the plunger usually remains stationary while an 15 outer cylinder or traveling barrel is reciprocally moved during operation of the pump.

This application covers improvements on my Patent No. 1,454,400, issued May 8, 1923.

In the operation of such pumps the normal 20 wear of the packing sometimes prevents the pump from priming in case the valves are not entirely surrounded by the liquid. This necessitates the frequent lifting of the pump from the bottom of a deep well to 25 repeat the same with the resultant expenditure and loss of time entailed thereby and it is one object of the invention to provide a packing which enables the pump to prime regardless of whether the valves are completely 30 submerged in the liquid or not.

The crude oil as it is pumped from the wells in most cases has a considerable amount of grit suspended therein. In the intervals when the pump is not in operation the grit which is in suspension in the oil standing in the pump above the packing will settle on the packing with valve construction as heretofore provided. When the pumping operation is resumed this grit 35 works its way between the packing and the cylinder and causes rapid abrasion of the packing. Another object of the invention is to provide a device which prevents grit from settling on the packing either during or between pumping operations and thereby avoids the rapid abrasion and wearing away of the packing which otherwise results when the pumping operation is resumed after the pump has been idle.

50 A further object is to generally improve deep well pumps and the packing therein.

Other further and more specific objects will become apparent as the specification proceeds.

In the accompanying drawing:—

Fig. 1 is a vertical view partially in section of a portion of a deep well pump, showing the traveling barrel or cylinder and the associated plunger equipped with the improved packing and devices of this invention;

Fig. 2 is a vertical sectional view on a larger scale than that of Fig. 1, showing the packing and the preferred embodiment of the device for preventing sediment from gathering on the packing, and,

Fig. 3 is a view similar to and on the same scale as Fig. 2, showing an alternative embodiment of a device for preventing grit from settling on the packing.

Similar numerals refer to similar parts throughout the several views.

The reciprocating barrel 10, the stationary plunger, generally indicated by the numeral 11, and the soft packing 12 are substantially identical with and perform the same functions as the corresponding elements in the above mentioned patent. The liquid is forced up through the plunger 11 by the reciprocation of the barrel. The packing 12 fits closely between the barrel and the plunger so that fluids cannot escape between the plunger and the barrel.

The plunger comprises an upper cylindrical member 13, preferably connected to a corresponding lower cylindrical member 14, by a sleeve 15, against which one end of a compression spring 16 presses. The cylindrical plunger can be made in one section instead of two, as shown, in which case a shoulder integrally formed on the plunger would be provided as a bearing for the spring. The cylinder is made in two sections, as shown, for easy assembling of the inverted cups 17, and the rings or collars 18 and 19, which are mounted on the member 13, between the packing 12 and the spring 16. The cups 17 are preferably made of leather or fibrous material. A head 20 is mounted on the upper end of the plunger so as to fit closely the inner periphery of the barrel 10. The lower end of the head 20 and the upper end of the collar 19 are each hollowed out adjacent their inner periphery to form concave-shaped seats into which the packing 12 is wedged by the pressure from the spring 16, thereby making fluid-tight connections between the plunger and the

collar 19, and the head 20 respectively. The wedging of the packing into the concave seats results in the spring pressure being applied eccentrically to the packing 12 with 5 the maximum pressure on the inner portion of the packing at its ends. As a result of this eccentric application of the pressure on the ends of the packing 12, the intermediate sections of the packing are thrust outwardly 10 so as to bear against the barrel 10 and make a fluid-tight connection between the barrel 10 and the packing.

The collars or rings 18 are provided with shoulders which permit liquid to enter the 15 inverted cups 17 whereby the cups are maintained in close contact with the barrel by hydraulic pressure. The wear on the exterior of the cups is thus compensated for and the cups in connection with the packing 12, 20 provide a device which is self-priming under any condition of operation to which such pumps are subjected.

The collars or rings 18 and 19, the inverted cups 17, and the packing 12 are in square 25 contact only on an annular surface adjacent the plunger. The spring and hydraulic pressure are thereby carried into the packing 12 eccentrically as above mentioned. The collars 18 by reason of their shoulders, 30 perform the dual function of contributing to the wedging the cups 17 against the barrel 10 by hydraulic pressure, and by eccentric application of the spring pressure to the packing 12, aid in the pressure of the ends 35 of the packing 12 against the plunger 11, and the intermediate sections of the packing against the barrel 10.

The head 20 is generally cylindrical in 40 shape and has its inner periphery bevelled outwardly with its upper edge relatively thin and tapering as shown. By this arrangement no horizontal surface is presented on which grit can settle from the liquid column above, when the pump is not operating, and 45 the possibility of grit working between the head 20 and the barrel 10 to the packing 12 is minimized. Such sediment as may occur will be washed off by the upward flow of liquid when pumping operations are resumed.

An alternative device for preventing settlement of grit onto the packing 12 is shown in Fig. 3, where the head 20 is replaced by a sleeve 21, a cup 22, and a plug 23. The 55 ends of the sleeve 21 fit closely inside the barrel 10. The middle portion of the sleeve is flattened for engagement by a wrench for threading onto the member 13. The lower end of the sleeve 21 is concaved for wedging engagement with the packing 12, similar to that of the head 20. The cup 22, which closely fits the member 13, is positioned between the sleeve 21 and the plug 23, and has its upper end bevelled to slope 60 downwardly towards the plug 23. The plug

23 is threaded onto the member 13 into contact with cup 22. A plurality of apertures 24 and 25 are provided in the plug to permit the liquid to flow upwardly therethrough during the pumping process. 70 These apertures slope outwardly and upwardly and are positioned so that grit suspended in the liquid column above the plug does not enter the plug. The lowermost of the apertures 25 are positioned adjacent the 75 bevelled top of the cup 22 in order that flow of liquid will remove any grit that may have settled on the top of the cup. The slope of the apertures 24 and 25 and of the top of the cup 21 is such as to cause the 80 outgoing fluid to scour out any dirt or grit. The close fit between the barrel 10 and the sleeve 21 and the cup 22 respectively, effectively prevents grit from reaching the packing 12.

Thus it will be seen that I have provided a device that delivers pressure onto the soft packing of pumps of the class described in such a way that the packing is forced at its ends against the plunger and at sections intermediate its ends against the barrel 10 to produce a tight joint and that I have provided additional packing in the form of cups which supplement the soft packing and assist in carrying the pressure onto the soft packing eccentrically. Improved means are also provided for minimizing the amount of grit which settles the packing during a cessation of pumping and which is so constructed that upward flow of liquid 95 scours off the grit and dirt which may have settled when the pump is not operating. 100

I claim:

1. In a device of the class described, a movable reciprocating barrel, a stationary plunger, and means adapted to form a fluid-tight joint between the barrel and plunger, comprising an element fixedly mounted on the plunger, expansible packing below said element, a plurality of collars slidably mounted on the plunger below said packing and having inverted cups between said collars fitting the inner periphery of the barrel, said collars and cups being in direct contact adjacent the plunger, and a compression spring suitably mounted to engage the lower of said collars whereby said packing is compressed by the spring and the hydraulic pressure from the cups. 115

2. In a device of the class described, a movable reciprocating barrel, a stationary plunger, and means adapted to form a fluid-tight joint between the barrel and plunger, comprising an element fixedly mounted on the plunger, expansible packing below said element, a plurality of collars slidably mounted on the plunger and having inverted cups between said collars fitting the inner periphery of the barrel, said collars and cups being in direct contact adjacent 120 125 130

the plunger, the upper end of the upper of said collars and the lower end of said element being bevelled adjacent the plunger to form upwardly and downwardly converging recesses, respectively, into which the packing is compressed and held by the spring pressure and the hydraulic pressure applied to the cups.

3. In a device of the class described, a
10 movable reciprocating barrel, a stationary plunger having an upper end portion within said barrel and in spaced relation thereto, an expansible packing between the plunger and barrel, and a cylindrical head member
15 mounted on the upper end of the plunger and closely fitting the inner periphery of said barrel, said head member having its upper end bevelled downwardly and inwardly from its outer periphery whereby upward flow of liquid from the plunger scours
20 the upper end of said head member, and a perforated plug mounted on the plunger with the perforations inclined outwardly and upwardly adjacent the bevelled portion of said head member.

4. In a device of the class described, a movable reciprocating barrel, a stationary plunger having an upper end portion within said barrel and in spaced relation thereto, an expansible packing between the plunger and barrel, and a cylindrical head member mounted on the upper end of the plunger and closely fitting the inner periphery of said barrel, said head member having its upper end bevelled downwardly and inwardly from its outer periphery whereby upward flow of liquid from the plunger scours
25 the upper end of said head member, and a perforated plug mounted on the plunger with the perforations inclined outwardly and upwardly adjacent the bevelled portion of said head member.

Signed at Tulsa, Oklahoma, this 16th day of September, 1924.

WALTER A. O'BANNON.
